BALL-RACKING COUNTER

Evangle Mistacu, St. Louis, Mo., assignor to Mina
Mistacu, St. Louis, Mo.

Application July 2, 1941, Serial No. 400,825

3 Claims. (Cl. 235—91)

This invention relates to improvements in game apparatus, and more particularly to a device which will register and count the number of times that a set of game balls have been placed in readiness formation for play.

One of the objects of this invention is to provide on a rack means generally used for grouping a set of playing balls in a predetermined geometric formation for subsequent play, a counter means which will enable the attendant or proprietor to ascertain just how much revenue he should receive from the players, and thus provide a check-up and deterrent for any attempt to escape payment for the use of the game-room.

Another object of my invention is to so combine a counter mechanism with a game rack of the kind described, that the grouping of the balls themselves within said rack will actuate the counter, and that upon release of the rack from the balls thus grouped, proper charge may be made for the game to be immediately played.

A further object of my invention is to so construct a device of the kind described, that there will be no interference with the normal use of the rack or its durability.

Other objects of my invention are to provide a device of the kind described, which will be neat and attractive in appearance, unobtrusive so as not to interfere with the proper and necessary use of the device, simple in operation and construction, light in weight, low in cost, and which will be otherwise satisfactory and efficient for use wherever deemed applicable.

To this end, my invention consists in the novel construction, arrangement and combination of parts herein shown and described, and the uses mentioned, as will be more clearly pointed out in the claims hereunto appended.

In the drawing, wherein like reference characters represent like or corresponding parts throughout the views.

Figure 1 is a top plan view of my improved rack about to be released from the playing balls properly grouped therein;

Figure 2 is a fragmentary perspective view showing that portion of the rack in association with the counter mechanism;

Figure 3 is a cross-sectional detail, showing the mounting of the counter and actuating means;

Figure 4 is an end view of the counter alone; and

Figure 5 is a top plan view of the parts shown in Fig. 4.

Referring more clearly to the drawing, wherein I have illustrated a preferred embodiment of my invention, there is indicated in Fig. 1, a set of playing balls for playing various sorts of games, as for example, pocket billiards or the like.

Play is generally done upon a table or other flat playing surface, but inasmuch as the latter does not form a part of my invention, it is not illustrated herein. In public places, or the like, a fee is charged for play, and an attendant arranges the set of playing balls for subsequent play by the set of players, or "racks" them up by a light enclosing frame or "rack," the latter

15 being so shaped so as to retain the set of balls in the predetermined geometric formation required by the rules of the game, the balls remaining so grouped upon release of the rack therefrom.

20 The number of times that the balls are racked up indicates the number of games that have been played, and the charge made therefor, and it is in order to reduce any attempts to avoid payment for racking up, which might occur intentionally or through misunderstanding, I have arranged a means for positively counting the number of times that a set of playing balls have thus been racked.

25 Although there are other than triangular shapes of racks, I have chosen to illustrate the triangular shape herein, said rack being commonly of wood, having the bounding sides 1, 2 and 3 to form a continuous enclosure within which the set of playing balls are arranged.

30 The balls within the rack are then rolled as a unit with the rack to the point on the playing table as desired, whereupon the rack is lifted, leaving the balls grouped in the predetermined play design.

35 Adjacent one of the corners of the rack I have arranged a counting or registering mechanism, whereby each racking up of the balls will be registered, and the registering device may be checked against the reported number of games.

40 A counter 4 having visible registering wheels 5 is secured to the corner of the rack or frame, as on the exterior portion, by means of a fastening screw 6 or the like, this counter being of any suitable type and mechanism that will be sufficiently compact to fit into the space required, and will operate efficiently. An operating lever 7 extends from the operating shaft 8 of the counter and may have an enlarged contact face 9 for engagement with an actuating rod 12 as will be 45 more clearly hereinafter described.

A casing or closure 11 may be positioned over the counter, as shown, and if desired, may be provided with a sight opening 14 to enable reading of the counter.

Each time that the lever 7 is moved in one direction and released, the register will be actuated one unit. Any suitable means may be used to perform this operation of the counter, as for example, the means shown.

A plunger or rod 12 is positioned so as to be movable into the path of the lever 7, to thereby engage the contact face 8 of the latter and actuate the register in the usual manner, this plunger extending slidably through the corner of the rack.

Although the lever 7 is provided with spring means (not shown) within the counter, to return the lever to initial position after each positive movement thereof, I have provided additional means to insure return of the plunger to normal position after each operation. To this end, I have interposed a bed of sponge rubber or other suitable resilient or spring material 13 between a fixed portion of the rack and a head or abutment 10 fixed to the inner end of the plunger. The head 10 may be of a general disk shape and anchored or embedded, particularly at its bounding edge, in the mass of rubber, while the rod 12 preferably extends loosely through the latter.

No matter in what order the balls are placed within the rack, thus provided with the counter and operating means, the final ball placed therein, will of itself, or by transmitting movement to another ball, press the disk with plunger in a movement outwardly of the rack, this movement being transmitted in turn to the counter lever.

Removal of the rack now will permit the counter to register this racking up operation on the counter dial, and the rack is then with the counter lever and plunger parts as shown in their full-line position in Fig. 3, the dotted-line position indicating the movement of the parts to their extreme position.

Having thus described my invention, it is obvious that various immaterial modifications may

be made in the same without departing from the spirit of my invention; hence I do not wish to be understood as limiting myself to the exact form, arrangement, combination and construction herein shown and described, or the uses mentioned, except as limited by the state of the art to which this invention appertains, and the claims hereunto appended.

What I claim as new and desire to secure by Letters Patent is:

1. The combination with a polygonal game rack for positioning a set of playing balls in a predetermined geometric formation for play upon removal of the rack, of a counter on said rack at one of the corners thereof for registering the number of times that said balls have been so arranged and removed from said rack, and means concealed within said rack at said corner and operably controlled solely by the placing of the balls within the rack for actuating said counter.
2. The combination with a game rack for positioning a set of playing balls therewithin in a predetermined geometric formation for subsequent play upon removal of said rack therefrom, a counter mounted on said rack for registering the number of times that the rack has been used to set said balls in playing arrangement, a plunger concealed within said rack, and a resiliently mounted disk for actuating said plunger and operable solely by the final ball placed in said rack to complete said geometric formation to actuate said counter.
3. The combination with a polygonal game rack for positioning a set of playing balls in a predetermined formation upon said removal of the rack, of a counter arranged at one of the corners of said polygon for counting each removal of the rack, a plunger at said corner and operable by engagement with the ball adjacent said corner to constitute the sole actuator of said counter, and a resilient cushion for resisting actuation of said plunger and arranged within said corner.

EVANGLE MISTACU.
